Primary Examiner—Celia A. Murphy*(74) Attorney, Agent, or Firm*—Ezra Sutton, Esq.(57) **CLAIM**

The ornamental design for a compact disc carrying case with two speakers, as shown and described.

DESCRIPTION

FIG. 1 is a perspective view of a compact disc carrying case with two speakers in a closed configuration embodying my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a perspective view of the compact disc carrying case with two speakers in an open configuration embodying my new design.

The broken lines showing portions of discs in FIG. 8 illustrate the portions of the design that form no part of the claim.
